United States Patent Office.

SAMUEL N. BATCHELDER, OF PRAIRIE DU CHIEN, WISCONSIN.

Letters Patent No. 71,953, dated December 10, 1867.

IMPROVEMENT IN TRY-SQUARES AND BEVELS.

The Schedule referred to in these Letters Patent and making part of the same.

TO ALL WHOM IT MAY CONCERN:

Be it known that I, SAMUEL N. BATCHELDER, of Prairie du Chien, in the county of Crawford, and State of Wisconsin, have invented a new and useful Improvement in Combined Try-Square and Bevel; and I do hereby declare that the following is a full, clear, and exact description thereof, which will enable those skilled in the art to make and use the same, reference being had to the accompanying drawings, forming part of this specification.

This invention relates to a new and useful combination of two tools, which are both indispensable to the joiner or worker in wood, as well as in iron or other metals; and it consists in attaching the blade of a try-square to the stock in such a manner that it can be set and fastened at any desired angle by operating a hook-slide and set-screws, as I will proceed to describe.

Figure 1 represents a section of the tool through the line $z z$ of fig. 2, showing a side view and the arrangements of the parts of which it is composed.

Figure 2 is a top or end view of the same, showing the scale or lines which indicate the different angles to which the blade may be set.

Similar letters of reference indicate corresponding parts.

A is the stock, and B is the blade. The blade is pivoted to the stock by the thumb-screw C. The stock is separated through its width from the top to the point a, so that the blade can drop to form an acute angle with the stock when desired. D is the hook-slide, which is operated and fastened in place by a set-screw, E, on the back of the tool. The thumb-screw passes through the slide with a screw-thread, and draws the slide against the back plate c, which plate has a slot through it in which the screw is moved. The back end of the blade extends back and forms a hook, as seen in the drawing at e. F is a spiral spring which is placed inside the face-plate d, and which is attached to the stock at f and to the blade at g. The tendency of this spring is to draw down the blade when the thumb-screws C and E are loosened. On the top of the stock there is a scale of degrees, as a guide in setting the blade to any desired angle.

As indicated in the drawing, the corner of the blade h stands at ninety degrees. When in this position the blade stands at right angles with the stock, and it is then a try-square. The blade need not necessarily be fastened in this position; and an important feature is that the operator is enabled to square his work by standing erect and noticing the position of the corner of the blade. If the corner stands at ninety degrees when the square fits the work the work is square or at right angles. This device obviates the necessity of stooping, and also the inconvenience occasioned by a bad light.

To set the plate at any desired angle, either acute or obtuse, it is only necessary to loosen the screws and adjust the sliding hook to the blade, then tighten the screws as before. The advantages of this arrangement are many, and must be obvious to all.

What I claim, and desire to secure by Letters Patent, is—

1. The blade B pivoted within the stock A, and provided with a hooked projection, e, by means of which, and the hook-slide D, the blade B may be set and held at any desired angle, substantially as described and for the purpose specified.

2. I claim the hook-slide D with the thumb-screw E, arranged and operating substantially as shown and described, for the purposes set forth.

3. I claim the spiral spring F, in combination with a combined try-square and bevel, substantially as described.

SAMUEL N. BATCHELDER.
